UNITED STATES PATENT OFFICE.

WILLIAM R. WARREN, OF WEST UPTON, MASSACHUSETTS.

DESIGN FOR A LADY'S HAT.

SPECIFICATION forming part of Design No. 13,821, dated March 27, 1883.

Application filed February 3, 1883. Term of patent 3½ years.

To all whom it may concern:

Be it known that I, WILLIAM RIED WARREN, a citizen of the United States of America, residing at West Upton, in the county of Worcester, of the State of Massachusetts, have invented and produced a new and original Design for Ladies' Hats; and I do hereby declare the same to be described in the following specification and represented in the accompanying drawings, of which—

Figure 1 is a top view, Fig. 2 a side elevation, and Fig. 3 a longitudinal and median section, of a hat with its body shaped in accordance with such design, which, to distinguish the hat in trade from others, I term the "Escalopia."

The design, or its leading feature, is mainly that of the scalloped body of one of the two valves of a sea-shell of the genus Pecten, without its hinge-flange, in the place of which, to complete the design, there is substituted a crescent-shaped neck and ear guard, extending from the terminal ribs of the body, in manner as represented in the accompanying drawings, in which the body portion A of the hat is shown in shape like the ribbed portion of one of the valves of the pecten or sea-shell, termed a "scallop," and as having extended from its lowermost ribs, in manner as represented, the crescent-shaped neck-guard B, which, if desirable, may be fluted. Within the body, and to project from it in manner as set forth and as auxiliary to said design, is an elliptical or oval-shaped annulus, C, for receiving and fitting to the head of a person, in order to sustain the hat thereon.

I claim—

The design, substantially as described, for a hat, the same consisting in the body scallop-shaped and the neck and ear guard crescent-shaped, and arranged with such body as set forth.

WILLIAM RIED WARREN.
